UNITED STATES PATENT OFFICE.

EMMANUEL M. DIALYNAS, OF BALTIMORE, MARYLAND.

DESIGN FOR A PIN AND PICTURE-FRAME.

53,707.

Specification for Design.

Patented Aug. 19, 1919.

Application filed May 21, 1919. Serial No. 298,802. Term of patent 14 years.

To all whom it may concern:

Be it known that I, EMMANUEL M. DIALYNAS, a subject of the King of Greece, residing at Baltimore, in the city of Baltimore and State of Maryland, have invented a new, original, and ornamental Design for a Pin and Picture-Frame, of which the following is a specification, reference being had to the accompanying drawing, forming part thereof.

The figure is a front elevational view of a picture frame showing my new design.

I claim:—

The ornamental design for a pin and picture frame as shown.

EMMANUEL M. DIALYNAS.
